(57) **CLAIM**

We claim the ornamental design for a hoop toy, as shown and described.

DESCRIPTION

FIG. 1 is a front view of a hoop toy according to our new design;

FIG. 2 is a rear view thereof;

FIG. 3 is a left side view thereof, the left side view being a mirror image of the right side view;

FIG. 4 is a top view thereof;

FIG. 5 is a bottom view thereof;

FIG. 6 is a top perspective view thereof;

FIG. 7 is a front view thereof; and,

FIG. 8 is a front view thereof.

FIGS. 1, 7, and 8 show the hoop toy adjusted to high, low, and medium heights, respectively, using an adjustment mechanism. The broken line portions of the figures, including the adjustment mechanism, represent unclaimed subject matter only and form no part of the claimed design.
